BODY POSITIONER ATTACHMENT FOR
CASKETS

Earl R. Reese and Albertus Upton, Newton, Ill.

Application November 14, 1947, Serial No. 786,012

5 Claims. (Cl. 27—12)

1

This invention relates to a body positioner attachment adapted to be demountably disposed in a casket, adjacent the bottom thereof and beneath the mattress or bedding for elevating one side of a corpse in order that a frontal view of the corpse can be obtained while looking down into the casket at an angle.

More particularly, it is an object of the present invention to provide a body positioner attachment capable of being readily adjusted for elevating one side thereof when the casket is open and which may likewise be readily adjusted to cause the positioner to assume a horizontal position at other times when the casket is not open.

A still further object of the invention is to provide a device of the aforescribed character of extremely simple construction which may be economically manufactured and sold and which is capable of being readily actuated for adjusting the positioner from a horizontal to a laterally inclined position with respect to the casket or conversely.

Various other objects and advantages of the invention will hereinafter become more fully apparent from the following description of the drawings, illustrating a presently preferred embodiment thereof, and wherein:

Figure 1 is a plan view of one embodiment of the invention;

Figure 2 is a longitudinal sectional view showing the positioner in an applied position;

Figure 3 is a transverse sectional view through a casket and showing the positioner in end elevation therein and in an elevated position;

Figure 4 is a perspective view of the positioner;

Figure 5 is a perspective view of one of the hook supporting brackets thereof;

Figure 6 is a view similar to Figure 3 of another embodiment of the invention;

Figure 7 is a fragmentary perspective view of a longitudinal side portion thereof, and

Figure 8 is a perspective view of a supporting bracket for use with the embodiments of Figures 6 and 7.

Referring more specifically to the drawings, and first with reference to the embodiment of the invention as illustrated in Figures 1 to 5, the body positioner attachment for caskets comprising the invention is designated generally 10 and includes an elongated rectangular frame 11 the side portions of which are connected by transverse rods or bars 12 and 13, preferably of different diameters and which combine with said frame to form an openwork supporting surface

2

on which a mattress or bedding, not shown, of a casket 14 is adapted to be supported.

As best seen in Figure 4, one longitudinal side of the frame 11 is provided with three depending supporting legs, each designated generally 15 and each of which includes two sections 16 and 17 having adjacent overlapping ends which are connected by pivot pins or the like 18. The upper section 16 of each leg 15 has its upper end turned inwardly to engage around a portion of said side of the frame 11 and may be secured thereto in any suitable manner as by welding, as indicated at 19. A connecting bar or link 20 is pivotally connected by pivot pins or the like 21 to the outer side of each of the lower leg sections 17 and adjacent the lower ends thereof and said bar or link 20 between two of the legs 15, is provided with a handle 22 which extends upwardly therefrom and by means of which the link 20 can be displaced longitudinally of the frame 11 for swinging the leg sections 17 upwardly and into positions substantially at right angles to the leg sections 16. The side portion of the frame 11, to which the legs 15 are attached is also provided 25 with an upwardly projecting handle 23 for lifting said side of the frame.

The other longitudinal side of the frame 11 has the shank end of a pair of hooks 24 suitably secured thereto in any suitable manner as by soldering or welding, as indicated at 19a and said hooks 24 rise from the outer side of the frame 11 and terminate at their upper ends in out-turned hooked portions or bills 25 each of which is adapted to detachably engage in an opening 35 26 of a hook supporting hanger or bracket 27 which is secured by fastenings 28 to the inner side of one of the longitudinal side walls of the casket 14, as best seen in Figure 3 and whereby the side of the frame 11, to which said hooks 24 are connected, is supported thereby in a slightly elevated position with respect to the casket bottom.

As best seen in Figure 4, the frame 11 is divided at the point 29 into sections, the right-hand or head section of which is longer than the left-hand or foot section, and it will be noted that the two hooks 24 are attached to the right-hand or head section and that two of the legs 15 are likewise attached to the head section. The pivot pin 21 of the leg 15 which is attached to the foot section may be detachably connected to the link 20 to enable the ready detachment of the foot section of the frame 11 so that by detaching the left-hand or foot section the right-hand or head section only may be utilized for a half couch

casket or the entire device may be employed as a unit for use with a full couch casket.

It will be noted that the hooks 24 will support the left-hand side of the frame 11, as seen in Figure 3 slightly above the casket bottom and if the leg sections 17 are swung into folded position, substantially parallel to the frame 11, the right-hand side of said frame will be supported on the upper leg section 16 and at substantially the same level as the left-hand side thereof. The handle 23 as well as the handle 22 protrudes from one side of the bedding of the casket to enable the handle 23 to be manually engaged for elevating the right-hand side of the frame 11, as seen in Figure 3 so that the handle 22 can then be actuated to swing the leg sections 17 to their extended positions and for supporting the frame 11 at an incline laterally, as seen in Figure 3, or said handle 23 can be manually engaged for supporting the right-hand side of the frame elevated while the handle 22 is manually actuated for folding the leg sections 17 and preparatory to positioning the frame in substantially a horizontal position. It will thus be readily apparent that the body positioner 10 affords an attachment capable of being readily applied to conventional caskets and which is adapted to support the casket bedding on which the corpse is positioned and by means of which the body of the corpse may be tilted transversely with respect to the longitudinal axis of the casket so that when looking into the casket from above and at an angle a frontal view of the body will be afforded.

Figures 6, 7 and 8 illustrate a slightly modified form of the positioner and which is designated generally 30 and which includes a frame corresponding to the frame 11 and which frame 11, as seen in Figure 6 is provided at the left-hand side thereof with hooks 24, corresponding to the hooks 24 of the body positioner 10 and which are attached to hangers or brackets 27 in the same manner as previously described and as illustrated in Figure 3. However, in lieu of the legs 15, connecting link 20 and handle 22, a bar 32 is secured at one end thereof to the right-hand side of the frame 11 and to the right of the joint 29 or to the head section thereof and said bar 22 extends upwardly on the outer side of the frame and has the upper end thereof folded back upon itself to provide a handle 33. The upwardly extending portion of the bar 32 is provided with a struck out tongue 34 which projects outwardly and downwardly and which is adapted to selectively and detachably engage in vertically spaced openings 35 of a hanger bracket 36 which is secured by fastenings 37 to the inner side of the right-hand side of the casket 14 or opposite to the hanger brackets 27. The bar 32 may be secured at its lower end by welding or otherwise to the right-hand side of the frame 11 and is sufficiently resilient so that the upper end thereof may be swung inwardly with respect to the frame to permit the tongue 34 to pass on the inner side of the hanger 36 and may be permitted to yield outwardly for engaging the terminal of the tongue selectively in any one of the openings 35 for supporting the right-hand side of the frame 11, as seen in Figure 6 at any desired elevation with respect to the left-hand side thereof or for supporting said frame 11 in substantially a horizontal position. The right-hand side of the frame 11 may also be provided with a handle 23 by means of which said side may be held elevated for engaging or disengaging the tongue from the openings 35. It will likewise be readily ap-

parent that the structure of Figures 6 to 8 may be utilized with or without the left-hand or foot section of the frame 11 and that the body positioner 30 is intended and readily adaptable for use in the same manner and for the same purpose as previously described with reference to the body positioner 10.

Various other modifications and changes are likewise contemplated and may obviously be resorted to, without departing from the spirit or scope of the invention as hereinafter defined by the appended claims.

We claim as our invention:

1. A body positioner for a casket comprising a supporting frame adapted to be disposed in the bottom portion of a casket for supporting a corpse thereon, and means for supporting one longitudinal side of the frame at different levels with respect to the other side thereof, said means comprising legs secured to and depending from said side of the frame and each formed of pivotally connected sections, a link connecting the lower, depending sections of said legs, and a handle connected to said link for moving it in a direction longitudinally of the frame for moving said depending leg sections to extended position or into folded position, substantially parallel to the frame.
2. A body positioner for a casket comprising a supporting frame adapted to be disposed in the bottom portion of a casket for supporting a corpse thereon, and means for supporting one longitudinal side of the frame at different levels with respect to the other side thereof, said means comprising a hanger bracket supported on the inner side of said casket, and a resilient bar fixed to said side of the frame and extending upwardly therefrom and provided with an outwardly projecting element detachably and selectively engageable with vertically spaced portions of the hanger bracket for supporting said side of the frame at various levels.

3. A body positioner for a casket comprising a supporting frame adapted to be disposed in the bottom portion of a casket for supporting a corpse thereon, and means for supporting one longitudinal side of the frame at different levels with respect to the other side thereof, hook brackets mounted on the inner side of and supported by the casket above said frame, and hooks secured to said other side of the frame and rising therefrom and pivotally engaging said hook brackets for supporting said other side of the frame at substantially a predetermined level above the casket bottom and for accommodating a lateral rocking movement of the frame when said means is actuated for raising or lowering the first mentioned side thereof.

4. A body positioner for a casket comprising a supporting frame adapted to be disposed in the bottom portion of a casket for supporting a corpse thereon, and means for supporting the longitudinal sides of the frame at different levels with respect to the casket bottom, said frame being formed of separable head and foot sections, and said means being connected to said head section for supporting said head section separately or for supporting the frame as a unit.

5. A body positioner for a casket comprising a supporting frame adapted to be disposed in the bottom portion of a casket for supporting a corpse thereon, and means for supporting one longitudinal side of the frame at different levels with respect to the other side thereof, said means comprising a hanger bracket supported on the inner

side of said casket, and a resilient bar fixed to said side of the frame and extending upwardly therefrom and provided with an outwardly projecting element detachably and selectively engageable with vertically spaced portions of the hanger bracket for supporting said side of the frame at various levels, and hook and hanger means for pivotally supporting the other side of said frame at a predetermined level above the casket bottom.
